(57) **CLAIM**

The ornamental design for a tape spool support for tape cartridge, as shown and described.

DESCRIPTION

FIG. 1 is a perspective view of a tape spool support for tape cartridge;

FIG. 2 is a top view thereof;

FIG. 3 is a front view thereof;

FIG. 4 is a rear view thereof;

FIG. 5 is a left side view thereof;

FIG. 6 is a right side view thereof; and,

FIG. 7 is a cross-sectional view thereof taken along the lines 7—7 of FIG. 2.

The bottom view of the tape spool support for tape cartridge contains no ornamental design and is omitted. The broken lines define the bounds of the claimed design, but form no part of the claimed design.
